COMBINED TEMPERATURE CONTROL PANEL UNIT AND SUPPORT FOR SOLDERING IRONS AND THE LIKE

James C. Sewell, 4301 78th Ave. N., Brooklyn Park, Minn. 55429, and Gaylon T. Westlund, 2014 Emerson Ave. N., Minneapolis, Minn. 55411

Filed Feb. 17, 1969, Ser. No. 15,800

Term of patent 14 years

Int. Cl. D13—03; D8—03
U.S. Cl. D26—1

FIG. 1 is a plan view of our new and improved design of a combined temperature control panel unit and support for soldering irons and the like;

FIG. 2 is a top plan view of the same, the bottom plan being a mirror image of the same;

FIG. 3 is a right end elevation view of the same;

FIG. 4 is a left end elevation view of the same; and

FIG. 5 is a rear end elevation view of the same.

The outline of the cutting tool in FIG. 1 is for illustrated purposes only.

The electrical cord is shown broken away in the views on the drawing to indicate indeterminate length.

We claim:

The ornamental design for a combined temperature control panel unit and support for soldering irons and the like, as shown and described.
